Des. 64,676

UNITED STATES PATENT OFFICE.

SAHATIEL G. MANDALIAN, OF NORTH ATTLEBORO, MASSACHUSETTS.

DESIGN FOR A BAG FRAME.

Application filed March 15, 1924. Serial No. 8,945. Term of patent 7 years.

To all whom it may concern:

Be it known that I, SAHATIEL G. MANDALIAN, a citizen of the United States, residing at North Attleboro, in the county of Bristol and State of Massachusetts, have invented a certain new, original, and ornamental Design for a Bag Frame, of which the following is a specification.

In the accompanying drawing which forms a part of this specification the figure is a perspective view of a bag frame embodying my new design.

I claim:

The ornamental design for a bag frame, as shown.

SAHATIEL G. MANDALIAN.
